UNITED STATES PATENT OFFICE.

WILLIAM A. KELLY AND CORNELIUS WELLS SMITH, OF HONOLULU, TERRITORY OF HAWAII.

HARROW.

No. 920,581.

Specification of Letters Patent.

Patented May 4, 1909.

Application filed September 5, 1908. Serial No. 451,887.

To all whom it may concern:

Be it known that we, WILLIAM A. KELLY and CORNELIUS W. SMITH, citizens of the United States, and residents of Honolulu, 5 Oahu, Territory of Hawaii, have invented a new and Improved Harrow, of which the following is a full, clear, and exact description.

The device relates to a harrow that can be 10 drawn by steam or other power from either end, and one object is to so construct the machine that it will be as light as possible consistent with proper work, and so that the machine will accommodate itself to any 15 character of ground.

It is a further purpose of the invention to so mount the teeth carried by the frame of the machine, that they will automatically take position for harrowing whether the machine 20 be drawn in one or the other direction; since a suitable draft attachment may be applied to either end of the machine.

It is a further purpose of the invention to so construct and mount the teeth, that they 25 will be in transverse series, alternate series acting to turn the soil, the intervening series being then inactive, simply riding over the ground, and being brought into service only when the machine is drawn from the oppo- 30 site end.

The invention consists in the novel construction and combination of parts illustrated, and to be hereinafter fully described.

In the drawings, Figure 1 is a plan view 35 of the improved harrow, Fig. 2 is a side elevation of the harrow, the teeth being arranged for operation when the machine is drawn, as indicated by the arrow; and Fig. 3 is a detail section, taken practically on the 40 line 3—3 of Fig. 1.

Similar characters of reference indicate corresponding parts in all the views.

In the construction of the machine, parallel beams A and B are employed as draft 45 beams, so that the harrow may be drawn with equal facility from either end. A series of stepped, toothed bars C connect the beams A and B, which bars at their straight or parallel portions, are in two members 10 and 11, 50 and said tooth-carrying bars C are pivotally connected in desired members by transverse bars 12, whereby the bars C are in longitudinal series or sets, as is best illustrated in Fig. 1. The tooth-carrying bars C are connected 55 with each other by links 14, and with the draft beams A and B, by suitable links 14^a,

and said draft beams A and B are provided with bolts 13, or their equivalents, for attachment to draft devices. Teeth 15 are carried by the straight sections of the bars C, 60 being pivoted between the members 10 and 11 by suitable pivot pins 17, and each tooth 15 is provided with a head 16 and each head 16 of a tooth is adapted, when the tooth is in operation, to bear against a stop pin 18, located at the dual section of a bar C, whereby 65 to hold such tooth in position to plow through the ground, while the teeth of the next or following series, simply ride over the surface of the ground, as is shown in Fig. 2, 70 and are only brought into action when the harrow is drawn from the opposite end. The teeth 15 are curved from their heads 16 downward, the curvature of the teeth in alternate series facing toward opposite ends of 75 the harrow, as is also shown in Fig. 2. The heads of the teeth extend in the direction of their curvature, as is also best shown in Fig. 2, so that as stated, when one set or series of teeth is active, the following set or series is 80 inactive.

The tie bars 12 may be secured to the tooth-carrying bars in any approved manner, as, for example, by means of the pins 18.

A harrow of the type described is constructed in sections, so jointed that as the harrow is drawn over the ground it will automatically accommodate itself to undulations and will equally dress all parts of the field over which it is drawn. 85

What we claim as new and desire to secure by Letters Patent is:

1. A harrow having draft connections at each end, tooth carrying bars connecting the draft connections, and a series of oppositely arranged pairs of teeth connected with each of said bars, the members of each pair being mounted to swing freely toward the other member of the pair. 90

2. A harrow having draft connections at each end, tooth carrying bars connecting the draft connections, and a series of pairs of teeth connected with each bar, the members of each pair being oppositely arranged and mounted for free swinging movement, and 95 means for limiting the swinging movement of each member in a direction away from the other member. 100

3. In a harrow, draft beams at each end of the harrow stepped tooth - carrying bars, 110 swinging connection between the tooth-carrying bars and the draft beams, and pivotal

connection between sundry of the tooth-carrying bars, coupling them in series, teeth mounted in transverse series in the said carrying bars, the teeth of adjacent series being 5 oppositely curved, and means for rendering one series of teeth active, and the adjacent series inactive, during the operation of the machine.

4. In a harrow, a tooth carrying bar, pairs 10 of teeth pivoted to each bar, the members of each pair being curved in opposite directions, and mounted to swing freely toward the other member of the pair.

5. In a harrow, the combination with draft 15 beams at each end, and tooth-carrying bars having swinging connection with the same beams, of teeth pivoted in the carrying bars and arranged in series, one series at the rear of the other, the teeth of opposing series be-

ing oppositely curved, heads for the said 20 teeth, the heads of one series of teeth facing the heads of the teeth of the next series, and stop devices carried by the toothed bars and adapted to engage with the heads of the teeth, acting in the operation of the machine 25 to bring the teeth of one series into action and release the teeth of the intervening series.

In testimony whereof we have signed our names to this specification in the presence of subscribing witnesses.

WILLIAM A. KELLY.
CORNELIUS WELLS SMITH.
